UNITED STATES PATENT OFFICE.

EDWARD B. HERMAN, OF WATERTOWN, MASSACHUSETTS.

CHECK-CONTROLLED ARTICLE-DELIVERY APPARATUS.

Application filed March 30, 1927. Serial No. 179,517.

My said invention relates to improvements in check controlled article delivery apparatus of the type designed for delivering wafers or similar articles and to an improved form of wafer for use in connection therewith, the apparatus and wafer being in fact specially designed for mutual co-operation.

The invention aims to provide an apparatus which may be very economically manufactured, and which will be simple and efficient in operation, the shape of the wafer in connection with the operation of the delivery apparatus facilitating the operation of the latter.

A further object is to provide an apparatus in which the wafers will be fully exposed to view and the shape of the latter and the container present a novel and distinctive appearance, forming thereby a self-advertising device.

With these and other objects in view, the invention includes the novel apparatus and article hereinafter described and defined by the appended claims.

What I at present consider the preferred embodiment of the invention is illustrated in the accompanying drawings in which:—

Figure 1 is a front view of the apparatus.

Fig. 2 is a side elevation partly in section.

Fig. 3 is a detail view in elevation of the back member.

Fig. 4 is a detail of the wafer, and

Fig. 5 is a section on line 5—5 of Fig. 3 partly broken away.

Referring by reference characters to these figures, the numeral 1 designates a back or main supporting member of suitable dimensions which may conveniently be of wood having its front face provided with a central longitudinal groove 1^a of a width and thickness to receive and permit the passage of a coin of the proper denomination say for example a penny, the groove being preferably flared at the upper end to facilitate the entrance of the coin.

A face plate 2 secured to the front face of the member 1 by suitable means such for example as screws, covers the open side of the groove 1^a thereby forming a coin chute. This face plate 2 forms the back of the wafer holding chamber. By making the back plate and face plate separate, I can economically and expeditiously form the coin chute by making a groove of the proper depth and

width in the back plate and convert this into a coin chute by merely applying the face plate. As the wafer which I have designed is triangular in shape, it is necessary to provide but two converging sides 3, 3 meeting at the front. I prefer to make these sides in the form of two glass plates or slabs as shown. The face plate 2 is of slightly less width than the back plate thereby forming rabbets 1^b in which the back edges of the glass plates are seated, while their front edges abut as shown. The side edges of the back plate are preferably beveled as indicated at 1^c so as to conform in slope to the incline of the glass plates.

For holding the glass plates in position I provide upper and lower brackets 4 and 5, having ends overlapping the inclined sides of the back plate and secured in any suitable manner.

The inner faces of the lower bracket member are provided with flanges or ledges 5^a upon which the bottom end edges of the glass plates rest, and the internal apex of this bracket is provided with a ledge or abutment 5^b upon which the front corner of the bottom triangular wafer rests. The bracket 4 is provided with a hinged cover 5^c which may be provided with a suitable lock, only the keyhole being shown.

As shown in Fig. 4 each wafer 6 is of triangular shape and has its rear edge beveled as indicated at 6^a and its front edge likewise beveled as indicated at 6^b. This beveling produces three relatively sharp corners, 6^a, 6^b and 6^c. The front corner rests on the abutment 5^b before referred to, it being understood that the wafers are placed in the holding chamber with the beveled faces uppermost.

For sustaining the rear corners, I provide a transverse shaft 7 journaled in suitable bearings 7^a secured to the back plate 1 beneath the lower edge of the face plate, which shaft carries toothed or winged wafer 100 engaging and releasing members 8, each of which preferably has four wings as shown, the back plate being recessed to receive these members as indicated at 1^e.

Retaining and releasing means is provided to cooperate with these wafer engaging and releasing members, which preferably takes the form of a substantially U-shaped wire 9 having its side arms slidably held in guides 9^a carried by the member 1. The bottom of

the loop supports a coin impact receiving plate 10 and the loop is supported in proper position, normally, by a leaf spring 11 having its ends secured to the bottom end of 5 the back member 1 by suitable clips or retaining devices 12.

When no coin is on the plate 10, the spring holds the U shaped member elevated so that its upper ends engage the depending wings 10 of the members 8 which causes the next succeeding wings to project into the wafer receiving chamber and thus support the rear corners α α' of the bottom wafer of the pile. Upon the insertion of a coin in the coin chute 15 this drops to the bottom and strikes the plate 11 which causes the spring to yield sufficiently to draw the ends of the U-shaped member 9 out of engagement with the depending wings of the wafer supporting devices 8, whereupon these rotate under the weight of the pile of wafers, allowing the bottom wafer to enter the delivery space 13.

Due to the beveled rear edges of the wafer, ample space is provided for the entry of the 25 next succeeding wing beneath the next lowermost wafer of the pile, and as the spring 11 immediately returns the upper ends of member 9 into normal and engaging position, but one wafer will be delivered and the 30 remainder held supported in the container until another coin is inserted.

The lower end of the back member 1 is provided with a bifurcated or recessed portion indicated at 11 which permits the coin 35 to tip over and drop into the coin receptacle 14, the fixed top of which 14^a receives the delivered wafer.

The coin receptacle is provided with a door 15, preferably in its bottom, capable 40 of being opened to withdraw the coins, which door is provided with a suitable lock (not shown).

While I have described my invention with considerable particularity it will be obvious 45 to those skilled in the art that various changes may be made without departing from the spirit of my invention.

In practice the brackets 4 and 5 may be formed as integral extensions of a sheet 50 metal casing having inclined sides to abut against and be secured to the inclined side edges of the back plate, which sheet metal

casing may be continued below the lower end of the back plate to form the coin receptacle, which of course would be provided 55 with a back closure wall (not shown).

I claim as my invention:

1. In a coin controlled article delivery apparatus a storage chamber of substantially triangular shape in cross section to receive 60 wafers of corresponding shape, said chamber having a wafer supporting abutment in one corner, and means for releasably supporting the opposite edge of the wafer comprising a pair of spaced rotary members having wings adapted to successively project into the path of the wafers, yieldably supported U-shaped member having its arms adapted to engage the wings of said members, and means for causing a coin to actuate said U-shaped member. 70

2. In a coin controlled article delivery apparatus a storage chamber having a fixed abutment for supporting one edge of the bottommost of a pile of articles, a pair of 75 spaced rotatable members having wings adapted to successively project into engagement with the other edge of the article, a substantially U-shaped member having arms slidably held with their ends in proximity 80 to said rotatable members, yieldable means for normally holding said arm ends in the path of said wings, a coin impact plate carried by said U-shaped member, and means for conducting a coin to said coin impact 85 plate.

3. In a coin controlled article delivery apparatus a storage chamber having a fixed abutment for supporting one edge of the bottommost of a pile of articles, a pair of 90 spaced rotatable members having wings adapted to successively project into engagement with the other edge of the article, a substantially U-shaped member having arms slidably held with their ends in proximity 95 to said rotatable members, a leaf spring yieldably supporting said U-shaped member and normally holding the ends of its arms in the path of said wings and a coin impact receiving plate carried in the base 100 of said U-shaped member.

In testimony whereof, I affix my signature.

EDWARD B. HERMAN.
